NONSKID ATTACHMENT FOR CRUTCHES
OR CANES

Frank J. Schroeder, Cleveland, Ohio

Application May 9, 1944, Serial No. 534,747

9 Claims. (Cl. 135—53)

This invention is a device for attachment to the bottoms of crutches or canes, and its purpose is to render the crutches or canes safe for use on icy walks or other slippery surfaces.

The device includes a cushion, desirably of usual appearance, and a spur that is reciprocable in a bore of the cushion and is shiftable at will between a position wherein its lower pointed end projects a substantial distance beyond the bearing surface of the cushion and a second position wherein said end is well up within the bore so as not to interfere with the customary functioning of the cushion.

Objects of the invention are to provide a device of the character above described that is very substantial, durable, and effective, yet relatively simple and inexpensive; that requires little alteration of the crutch or cane in the attachment of the device thereto; that is convenient of manipulation for the purpose of projecting and retracting the spur; that is neat and compact, light of weight, and attractive of appearance so that its presence in the structure of a crutch or cane is not objectionable in any way; that is adapted to be filled or packed with a suitable grease to insure ease of operation at all times and preclude the presence of moisture and consequently avoid freezing; wherein the spur is readily accessible for sharpening and for adjustment to compensate for its gradually changing length and more especially for the wearing away of the cushion, and wherein provision is made to prevent accidental retraction of the spur under the weight of the user.

The foregoing objects, with others hereinafter appearing, are attained in the embodiment of the invention illustrated in the accompanying drawing wherein Fig. 1 is a side elevational view of the device attached to the bottom of the shaft of a crutch or cane; Fig. 2 is a central longitudinal section through the device, showing the end of the crutch or cane shaft in elevation, the plane of section being indicated by the line 2—2 of Fig. 1; Figs. 3 and 4 are sectional details on the respective lines 3—3 and 4—4 of Fig. 1; Fig. 5 is a perspective view of the shaft and its operating handle and the cam or eccentric that is adapted to be fixed to the shaft; Fig. 6 a perspective view of the parts, in separated condition, of a structure that carries the spur and is reciprocable within the casing of the device, and Fig. 7 is a perspective view of the bottom of the casing.

The device includes a cylindrical casing 1 that is fitted to the shaft 2 of a crutch or cane, desirably by reducing the end of the shaft to pro-

vide a tenon 3 that snugly fits within the casing and to which the casing is fastened by screws 4. Thus, a shoulder 5 is provided which takes the thrust of the casing when the weight of the user is imposed upon the crutch or cane. A relatively thick bottom wall 6 fits within the lower end of the cylindrical casing 1 and has a peripheral flange 7 against which the end of the tubular wall of the casing bears. The said tubular wall is attached to the end wall 6 by making depressions 8 in the former wall that engage within an angular groove 9 of the end wall. The wall 6 has a central bore 10.

Reciprocably mounted within the casing 1 is a structure designated generally by the numeral 12. This structure comprises a sleeve 13, a yoke 14, and a cross bar 15, the latter being stepped at its ends and shaped to fit within the lower end of the sleeve 13, the stepped formation providing flanges 16 that bear against the end of the sleeve. The parts of the structure 12 are suitably secured together, as by pins or rivets, as shown, or by welding. The yoke 14 includes abutments 18 and 19; the sleeve 13 has a split 20 that extends throughout its length on one side, and a shorter longitudinal split 21 on the other, the latter split opening through the top edge of the sleeve, and the cross bar 15 is provided with a threaded hole 22 that is coincident with the axis of the sleeve 13 and is in alignment with the bore 10 of the end wall 6.

Occupying the yoke 14, and arranged for cooperation with the abutments 18 and 19, is a cam or eccentric 25 that is pinned or otherwise secured to a shaft 26 which is journaled at its ends in diametrically aligned bearing apertures in the cylindrical wall of the casing 1, said wall being made thicker or reinforced in the region of said apertures, as appears in Fig. 3.

To an extension 27 on one end of the shaft is pinned or otherwise fastened an operating handle 28, which serves incidentally to prevent longitudinal movement of the shaft in one direction, and movement of the shaft in the opposite direction is prevented by a pin 29 that extends through the shaft adjacent the inner end of the bearing next to said handle.

Stops 30 extend from the side of the casing 1 above and below the end of the shaft 26 to which the operating handle 28 is attached and serve, through cooperation with the handle, to limit the throw of the shaft 26, and consequently that of the cam or eccentric 25, to 180°. In such a swing of the cam or eccentric, the structure 12 is given its maximum movement within the casing; and, for a reason which will hereinafter be explained,

when the cam or eccentric is swung in a direction toward the bottom of the casing, it passes a few degrees beyond dead center, so to speak, in which position it is stopped by engagement with the solid side member of the yoke 14, the opposite side member being slotted, as clearly shown in Figs. 2, 3 and 6, to allow clearance for the cam or eccentric as the latter swings from one end toward the other of its throw. Carried by the operating handle 28 is a leaf spring 32 that engages 10 depressed seats 33 adjacent the stops 30 when the operating handle is moved into contact with said stops.

Applied to the lower end of the casing 1 is the upper socketed end of a cushion 35 of rubber, or other suitable resilient material which desirably has the appearance and physical characteristics of standard crutch or cane caps or cushions; and a central longitudinal bore 36 of the cushion 35 registers with the bore 10 of the end wall 6. Slidably fitting said bores is a spur 40 that is preferably made of high quality steel, and hardened. Its lower end is shown as provided with a slot 41 for the reception of a thin blade by which the spur may be rotated, and its upper end is threaded and screwed into the threaded hole 22 of the cross bar 15 that constitutes a part of the structure 12. By reason of the construction just described, the spur may be adjusted with respect to said structure to compensate for wear of the cushion 35, as well as to take care of the gradually changing length of the spur due to wear and occasional sharpening. Also, by virtue of this construction, the spur may be taken out and replaced without dismantling or removing the device or withdrawing the cushion 35 from the casing.

The sleeve 13 is constructed of resilient material, and by reason of its being longitudinally split, it yields circumferentially and frictionally engages the peripheral wall of the casing 1. The structure 12, of which the sleeve 13 forms a part, is prevented from turning within the casing by a pin 42 that is carried by the casing wall and projects into the slot 20 of the sleeve 13. To insure easy operation of the working parts at all times, the casing 1 is packed with a suitable grease, the presence of which excludes moisture from the casing and consequently avoids freezing in cold weather which would interfere with satisfactory action of the movable parts. The fact that the structure 12 is open from end to end prevents the grease from interfering with the reciprocatory movement of said structure.

While I have herein shown and described a very satisfactory and practical embodiment of the invention, I wish it to be understood that I do not limit myself to the present structural details further than required by the terms of the appended claims. The illustrated embodiment is a construction that I have used on crutches, and where I have applied the same to relatively slender canes, I have reduced the diameter of the casing 1, relative to its length, and have shifted the shaft slightly to one side of the center of the casing and have changed the proportions of the cam 25 accordingly in order to adapt the mechanism to the casing of lesser diameter. Such a modification is so nearly like the construction shown in the drawing that further illustration in addition to the above explanation is deemed unnecessary.

In the spring, after freezing weather has passed, the spur 40 should be screwed up into the structure 12 as far as it will go so as to protect it 70

from unnecessary wear in case the cushion 35 becomes worn away enough to expose the spur if the latter were retracted only as far as could be accomplished through the operation of the handle 28; and the spur should be left in this condition until freezing weather sets in in the fall when it will then be readjusted in proper relation to the prevailing plane of the bearing surface of the cushion. This precaution also avoids the marking of floors or other surfaces in case the cushion wears away sufficiently to permit the spur, in its normally retracted position, to engage such surfaces.

Having thus described my invention, what I claim is:

1. A device comprising a casing for attachment to the bottom of a crutch or cane, said casing having an opening, a structure reciprocable in the casing, a spur having adjustable connection with the structure and projecting through the bottom of the casing, and manually operable mechanism within the casing for reciprocating the structure, said mechanism being characterized by a handle exterior of the casing having operative connection through the aforesaid opening with said mechanism for actuating the latter, the casing being adapted to receive a cushion member about the lower end thereof that is provided with a bore for the passage of the spur.
2. A device comprising a casing for attachment to the bottom of a crutch or cane, said casing having an opening, a structure reciprocable in the casing, manually operable mechanism within the casing for reciprocating said structure, said mechanism being characterized by a handle exterior of the casing having operative connection through the aforesaid opening with said mechanism for actuating the latter, the casing being adapted to receive a cushion about the lower end thereof, said cushion and the bottom of the casing having aligned bores, and a spur slidably fitting said bores and threadedly connected at its inner end to said structure.
3. A device comprising a grease-retaining casing for attachment to the bottom of a crutch or cane, a structure reciprocable in the casing and open throughout its length for passage of grease, the bottom of the casing being provided with a bore, a spur connected to the structure and projecting through said bore and having a sliding fit therein, the casing having an opening, and manually operated means extending through said opening and adapted to reciprocate said structure, said casing being adapted to receive a cushion member about the lower end thereof that is provided with an opening for the passage of the spur.

4. A device comprising a grease-retaining casing for attachment to the bottom of a crutch or cane, a structure within the casing frictionally engaging the peripheral wall thereof and open from end to end for the passage of grease therethrough, manually operable mechanism within the casing for reciprocating said structure, and a spur connected at its inner end to said structure.

5. A device comprising a grease-retaining casing for attachment to the bottom of a crutch or cane, a hollow structure within the casing yieldingly engaging the peripheral wall thereof and open from end to end for the passage of grease therethrough, manually operable mechanism within the casing for reciprocating said structure, the casing having a bore in the bottom thereof and being adapted to receive a cushion mem-

ber about its lower end that is provided with a bore registering with the bore in the bottom of the casing, and a spur slidably fitting said bores and adjustably connected at its inner end to said structure.

6. A device comprising a cylindrical casing for attachment to the bottom of a crutch or cane, a longitudinally split cylindrical shell within the casing frictionally engaging the peripheral wall thereof, a yoke secured to the top of the shell and including vertically spaced abutments, a bar extending across and secured to the bottom of the shell, said bar having a threaded hole, the axis of said hole being coincident with that of the shell, the bottom of the casing having a bore in axial alignment with said hole, a shaft supported by and between opposed portions of the peripheral wall of the casing, said shaft extending through the aforesaid yoke, a cam secured to the shaft within said yoke for cooperation with the aforesaid abutments, one end of the shaft projecting outwardly beyond the adjacent side of the casing and operable by a handle secured to the projecting end thereof, the handle and casing having parts that cooperate to limit swinging movement of the handle, yielding means for retaining the handle at each limit of its swinging movement, the casing being adapted to receive a cushion member about the lower end thereof which member is provided with a bore registering with the previously mentioned bore, and a spur slidably within said bores and threaded at its inner end for adjustment within the threaded hole of the aforesaid bar.

7. A device comprising a cylindrical casing for attachment at its upper end to the bottom of a crutch or cane, a circular bottom wall fitted within the lower end of said casing and having a peripheral flange against which the end of said casing bears, the wall above said flange having a circumferential groove into which parts of the casing are depressed for attaching said wall to the casing, the casing being adapted to receive a cushion member about the lower end thereof, the aforesaid bottom wall and said cushion member having aligned bores the axes of which are coincident with that of said casing, a structure

reciprocable within the casing, the structure including at its lower end a part having a threaded hole in axial alignment with the aforesaid bores, a spur slidably within said bores and having its upper end threaded and screwed into said threaded hole, manually operable mechanism within the casing for reciprocating said structure, the casing having means to limit the movement of said structure.

10 8. A device comprising a casing for attachment at its upper end to the bottom of a crutch or cane, a bottom wall fitted to the lower end of said casing, the casing being adapted to receive a cushion member about the lower end thereof, the aforesaid bottom wall and said cushion member having aligned bores the axes of which are coincident with that of said casing, a structure reciprocable within the casing, the structure including at its lower end a part having a threaded hole in axial alignment with the aforesaid bores, a spur slidably within said bores and having its upper end threaded and screwed into said threaded hole, manually operable mechanism within the casing for reciprocating said structure, the casing having means to limit the movement of said structure, the mechanism assuming a condition when the spur is projected that positively blocks retraction of the spur.

15 9. A device comprising a casing for attachment at its upper end to the bottom of a crutch or cane, a bottom wall fitted to the lower end of said casing, the casing being adapted to receive a cushion member about the lower end thereof, the aforesaid bottom wall and said cushion member having aligned bores the axes of which are coincident with that of said casing, a structure reciprocable within the casing, a spur slidably within said bores and having connection at its upper end with said structure, manually operable mechanism within the casing for reciprocating said structure, the casing being provided with stops, and yielding means associated with said manually operable mechanism for engagement with a selected one of said stops to hold said structure in
